(57) **CLAIM**

The ornamental design for a wire and cable package manufacturing jig, as shown and described.

DESCRIPTION

FIG. 1 is an isometric view of a cart according to our design; FIG. 2 is a front view thereof; FIG. 3 is a top view thereof; FIG. 4 is a bottom view thereof; and, FIGS. 5 and 6 are side views thereof.

Broken lines having repeated short dashes in the Figures are for illustrative purposes only and form no part of the claimed design. Shade lines having a combination of long and short lines in the Figures show contour and not surface ornamentation.
